UNITED STATES PATENT OFFICE

169,847

SET OF PLAYING CARDS

Mahlon Inman, Nashville, Tenn.

Application January 12, 1953, Serial No. 23,106

Term of patent 14 years

(Cl. D34—13)

To all whom it may concern:

Be it known that I, Mahlon Inman, a citizen of the United States, residing at Nashville, in the county of Davidson and State of Tennessee, have invented a new, original, and ornamental Design for a Set of Playing Cards, of which the following is a specification, reference being had to the accompanying drawing, forming a part hereof.

Figs. 1 to 12 inclusive show the 48 cards in a set of playing cards, showing my new design. The cards are of no appreciable thickness, and the backs thereof have a conventional appearance.

I claim:

The ornamental design for a set of playing cards, as shown and described.

MAHLON INMAN.
